UNITED STATES PATENT OFFICE.

FRANK J. LOSS, OF DETROIT, MICHIGAN.

SIGNAL DEVICE.

Application filed April 3, 1924. Serial No. 703,908.

To all whom it may concern:

Be it known that I, FRANK J. LOSS, a citizen of the United States, and resident of Detroit, county of Wayne, and State of Michigan, have invented certain new and useful Improvements in Signal Devices, of which the following is a specification, and which are illustrated in the accompanying drawings, forming a part thereof.

10 This invention relates to signal devices, and more particularly to signal lamps and signal banners or targets therefor.

One of the objects of the invention is the provision of a signal target each side of 15 which is adapted to be utilized for signal purposes.

Another object of the invention is the provision of a new and improved combined lamp and signal target in which the target 20 is composed of a minimum number of parts and when applied to the lamp will not interfere with the opening and closing of the door or closure for the same.

A further object of the invention is the 25 provision of a new and improved signal target or banner that is simple in construction, cheap to manufacture, easily assembled on the lamp, that is efficient in operation, is not likely to become broken or get 30 out of order, and that may be applied to existing lamps without modifying the same.

Other and further objects and advantages 35 of the invention will appear from the following description, taken in connection with the accompanying drawings, in which—

Fig. 1 is a plan view of a signal lamp showing the invention in position thereon;

Fig. 2 is a rear elevation thereof;

Fig. 3 is a front elevation;

40 Fig. 4 is a side elevation; and

Fig. 5 is a perspective view of one of the elements of the signal target.

On the drawings the reference character 45 10 designates a signal device which for the purpose of simplicity in illustration and convenience of description is herein disclosed, by way of example, as being a signal lantern.

This lantern comprises the casing 11 which 50 is preferably cylindrical in form although it is understood that it may be otherwise.

The casing is provided with light passages or openings arranged 90° apart in the walls thereof, as is usual in such constructions.

These openings are surrounded with flanges 12, 13, 14 and 15 in which, if desired, the lenses 16 and 160 may be mounted. The lenses have a common focal point in which the source of light is located, as is the usual practice. The lenses are held in position by suitable clamp members 17 60 which engage beads 18 about the tubes or flanges 12, 13, 14 and 15, respectively.

What may be termed, for convenience of description, the front wall of the casing 11, may be in the form of a sliding door 31 65 which is adapted to be raised to afford access to the interior of the casing 11, as indicated by the partially raised position of the door, as shown in Fig. 3. The door 31 carries the flange or sleeve 15.

Suitable signal members, banners or targets 70 19 are employed for indicating by distinctive colors certain signals and for intercepting those rays of light emanating from the lamp that indicate different signals. 75 These targets comprise signal wings 20, 21, 22 and 23, which are adapted to be arranged vertically between the light passages or lenses 16 in the casing 11.

Suitable means are provided for securing 80 the signal wings in position on the lamp. As shown, the wings are arranged in pairs and are provided with a suitable connecting member 24 which holds them in spaced relation and radially of the lamp 10 when the 85 same are in position on the lamp. The wings and their connecting members may be, and preferably are, stamped from sheet metal. Each connecting member 24 is provided with an opening 25, see Fig. 5, which 90 engages over the flanges or tubes through which the light is emitted. These members are adapted to fit the contour of the casing 11, being curved in the present instance, as indicated in Fig. 1.

In assembling the device the connecting members 24 are placed on the flanges or sleeves 12 and 14, leaving the flange or sleeve 15 on the door 31 unencumbered, whereby said door may be opened and 100

closed without moving any portion of the target. By this arrangement the door 31 may be opened to have access to the interior of the casing 11 or for filling the cup or bowl of the lamp, if an oil type of lamp be employed, without in any way being affected or interfered with by wings of the target.

Where it is desirable to apply the target to lamps already in service, without modifying the lamp in any way, the connecting members are held in position on their respective sleeves by means of a plate 26 which is detachably secured to the wings 21 and 22 at the back of the lamp as by means of the bolts 27. This plate is so arranged that when applied it will draw the connecting members 24 against the sleeves or flanges 12 and 14 with sufficient force to hold the parts firmly in assembled relation. If desired registering openings may be provided in flanges at the top and bottom of the casing 10 and in the connecting member 24 for receiving fastening means 28 for securing said members in position on the lamp.

If the signal target be employed with an oil lamp, the wing 20 may be provided with a notch 29 to receive the outer end of the wick operating member 30. One of the connecting members 24 may be provided with an opening to permit access to the peep hole or observation opening 32.

As is usual in such constructions, the lenses 16 are of one color and the lenses 160 of another. The sides of the wings are painted or colored on the side adjacent to each lens to correspond to the color of the light from said lens. If the lenses 160 are red, for instance, the sides of the wings 21 and 22 and the wings 20 and 23 adjacent to said lenses will be red.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. A signal device comprising a signal lamp having a casing provided with a plurality of light passages arranged in pairs, the members of each pair facing in opposite directions, one pair transmitting rays of light of one color and the other of another color, and wings integrally connected together in pairs arranged vertically between the passages, the faces of said wings adjacent a light passage being colored to correspond with the color of the rays transmitted through said adjacent light passage and means for connecting said pairs of wings together.

2. A signal device comprising a signal lamp having a cylindrical casing, a plurality of light passages through said casing for transmitting light rays of different colors for signal purposes, wings connected together in pairs and secured to said casing and extending radially outwardly therefrom between said passages, the faces of said wings adjacent to said passages being of a color to correspond with the color of the light rays transmitted through said passages, respectively.

3. A signal device comprising a lamp having a casing provided with a door opening and a plurality of light passages, a closure for said opening, said closure being provided with a light passage, signal wings extending outwardly from said casing between said passages, and means for supporting said wings independently of said closure, said wings being connected together in pairs.

4. An attachment for signal lanterns comprising two signal wings and a connecting member between said wings, said member being provided with an opening, the inner faces of said wings being of one color and their outer faces of another, for constituting signals.

5. A signal device comprising a lamp having a casing provided with a door opening at the front thereof, and a plurality of light passages, a closure for said opening, said closure being provided with a light passage, said passages being arranged 90° apart and the oppositely arranged passages being adapted to transmit light rays of the same color but of a different color from that transmitted by the remaining passages, a pair of signal wings for each side of said lamp, a connecting member for each pair of wings, said connecting member conforming to said casing, and means for independently securing each pair of wings in position on said lamp.

6. A signal device comprising a lamp having a casing, tubular flanges extending outwardly from said casing forming light passages, a pair of signal wings, a connecting member for said wings, said member provided with an opening for engaging one of said tubular flanges and means to hold said connecting member on said tubular flange.

7. A signal device comprising a lamp provided with a casing, tubular flanges extending outwardly from said casing to form light passages, a pair of signal wings, a connecting member for said wings, said connecting member conforming to said casing and provided with an opening for engaging one of said tubular flanges, a second pair of signal wings and connecting member for engaging a tubular flange at the

opposite side of said lamp and means for engaging a wing of each pair for holding said connecting members on said flanges.

8. A signal device comprising a lamp provided with a casing having tubular members providing light passages, two sets of signal wings, each set comprising two wings and a connecting member, said connecting

member conforming to the shape of said casing and provided with means for engaging one of said tubular members, and means engaging said connecting member and casing for holding said wings on said casing so that each wing will be between two light passages.

FRANK J. LOSS.
